(57) **CLAIM**

We claim the ornamental design for an expandable pet gate, as shown and described.

DESCRIPTION

FIG. 1 is a perspective view of an expandable pet gate showing our design, the expandable pet gate shown in an expanded condition;

FIG. 2 is a perspective view thereof, the expandable pet gate shown in an unexpanded condition;

FIG. 3 is a front view thereof;

FIG. 4 is a rear view thereof;

FIG. 5 is a right side view thereof, the opposite side to that shown being a mirror image thereof; and,

FIG. 6 is a top view thereof.

In the drawings, the broken lines are for illustrative purposes only and form no part of the claimed design.
